UNITED STATES PATENT OFFICE.

DURAND A. REESE, OF PHILADELPHIA, PENNSYLVANIA.

DESIGN FOR A BADGE.

SPECIFICATION forming part of Design No. 27,451, dated August 3, 1897.

Application filed April 10, 1897. Serial No. 631,631. Term of patent 14 years.

To all whom it may concern:

Be it known that I, DURAND A. REESE, a citizen of the United States, residing in the city of Philadelphia, Pennsylvania, have invented and produced a new and original Design for a Badge, of which the following is a specification, reference being had to the accompanying drawing, forming part thereof.

The leading features of my design are the half-oval plate containing on its face an open Bible with clasped hands across, a panel for suitable inscription depending therefrom, a flag, a scroll-plate pendant, and an ornamental shield having the figure of a woman holding a flag in her left hand, scales in her right hand, clasped hands, and underneath a panel for appropriate inscription.

A represents a shield, on the face of which

are the following characteristics: B, the representation of the figure of a woman; C, a flag; D, scales; E, clasped hands; F, panel; G, ornamental scrolls, said parts composing lower part of emblem; H, a scroll-plate pendant; J, chains; K, flag; L, a panel above; M, half-oval plate, upon face of which is an open Bible; O, clasped hands across same; P, ornamental scrolls composing the upper parts of the emblem.

I claim—

The design for a badge, as herein shown and described.

DURAND A. REESE.
